UNITED STATES PATENT OFFICE

FRANK H. RUTHERFORD, OF CHICAGO, ILLINOIS.

AUTOMATIC AIR-BRAKE COUPLING FOR RAILWAY-CARS.

No. 853,424.

Specification of Letters Patent.

Patented May 14, 1907.

Application filed September 17, 1906. Serial No. 334,903.

To all whom it may concern:

Be it known that I, FRANK H. RUTHERFORD, a citizen of the United States, and a resident of Chicago, in the county of Cook and State of Illinois, have invented a certain new and useful Improvement in Automatic Air-Brake Couplers for Railway-Cars, of which the following is a full, clear, and exact specification.

15 My invention relates to automatic couplers for the pipe-lines of railway-cars, and its object, besides accomplishing those usual functions for which it is intended, is to so connect the same to the car, or to the draw-bar of the car, that the twist of the same during engagement is reduced to a minimum.

Another object is to so construct and dispose of the spring for automatically returning it to its normal position, that the presence of said spring will not interfere with any part of the car. This I accomplish by the means hereinafter fully described and as particularly pointed out in the claims.

In the drawings:—Figure 1 is a side view 25 of the ends of two cars coupled together, and having my improved automatic couplers applied thereto. Fig. 2 is a front end view of my improvements detached from the car and with its engaging head broken away. Fig. 3 is a rear end view, showing a portion of the abutting spring broken away. Fig. 4 is a side view of my invention attached to the end of a car, and disengaged. Figs. 5, 6, 7, 8, and 9, are views of details of my invention.

35 Referring to the drawings, A represents a coupler-head of any suitable construction, having a waist of narrower proportions consisting of a bar *a* extending rearwardly therefrom in alignment with its axis. The rear 40 end of this bar *a* enters the apex of and, preferably, extends centrally through a conical-shaped body *B*, which latter passes through and is sealed in a suitable opening *c* in a hanger *C* secured to and depending from the 45 underside of the draw-bar of the regular car-coupler *D*. The body *B* attains its greatest diameter back of the hanger *C*, and its rear end is provided with a circumferential flange *d* exceeding in diameter the opening *c* of the hanger *C*, and provides an annular shoulder 50 that bears forward against the hanger under sufficient pressure to keep the coupler in a horizontal position. The waist of the coupler is provided with a bail *e*, consisting of a horizontal piece of metal with downturned ends secured thereto, and the weight of the

forward end of the coupler is sustained by one or more links *E*, suspended from the forward end of a bracket *F* whose rear end is secured to the hanger, substantially as 60 shown. These links also prevent the automatic coupler from twisting on its axis to any great extent when brought into engagement. This tendency of the coupler is also resisted by providing the shoulder made by the flange *d* with forwardly projecting equidistant tenons *f*, *f*, that enter correspondingly-shaped radial recesses *f'*, *f'*, made in the marginal portion of the rear face of the hanger *C*, surrounding opening *c*.

70 My improved automatic coupler is kept normally at the limit of its forward movement by the pressure brought to bear against its rear end by a comparatively powerful spring *G*, which is slightly C-shaped, and has 75 its upper down-turned end secured, preferably, to the rear of hanger *C* above opening *c*, and its lower upturned end *g* pressing forward against the rear end of the coupler. The coupler is designed to tilt upward or 80 downward, and to be capable of a slight lateral obliquity in order to meet the exigencies of its use. In order, therefore, to permit this, I convex the rear end of the body of the coupler and provide the center thereof with a 85 somewhat hemispherical boss *h*, against which the lower end of spring *G* presses. Extending rearwardly and centrally from boss *h* is a short guide-bar *H* which may be an extension of the bar constituting the waist of 90 the coupler, or consist of a separate element. This guide-bar extends through an opening *j* in the adjacent end of spring *G*, which is shaped somewhat like the keyhole of an old-fashioned door-lock, to provide passage and 95 play for a fin *J* projecting downward from said guide-bar *H*. This fin limits the rotation or twist of the coupling during its engagement and while pushed back to such position that the tenons *f* are out of engagement with 100 recesses *f'*. The rear extremity of guide-bar *H* is provided with a boss *I*, which is secured in place by a suitable nut or other means, and has its side next the spring made hemispherical. The end of spring *G*, located between bosses *h* and *I*, is free to adjust itself 105 to the positions into which it may move without binding, which it might do if said bosses presented a flat engaging surface thereto.

I do not wish to be confined to the exact 110 shape or even the position of spring *G*, as shown, as it could be disposed horizontally, if

desirable. This kind of a spring, made of flat material, enables me to greatly economize space back of the hanger, and combine the functions of means for guiding the coupler and preventing unlimited rotation on its axis and means for returning it to its normal position.

What I claim as new is:—

1. The combination with a car-coupler of an automatic air-brake coupler comprising a longitudinally yielding body supported by and movable with said car-coupler, and a spring of flat material engaging and normally keeping the same at the limit of its forward movement.
2. The combination with a car-coupler of an automatic air-brake coupler comprising a longitudinally yielding body supported by and movable with said car-coupler, and a spring of flat material engaging the rear end of said air-brake coupler and normally keeping the same at the limit of its forward movement.
3. The combination with a car-coupler of an automatic air-brake coupler comprising a longitudinally yielding body supported by and movable with said car-coupler, and a spring of flat material one end of which is permanently secured and the other end of which engages and normally keeps said air-brake coupler at the limit of its forward movement.
4. The combination with a car-coupler of an automatic air-brake coupler comprising a longitudinally yielding body supported by and movable with said car-coupler, and a spring of flat material one end of which is permanently secured above the air-brake coupler and the other end of which engages and normally keeps said coupler at the limit of its forward movement.
5. An automatic coupler for the train-pipes of cars comprising a longitudinally yielding body, and a substantially C-shaped spring, one end of which is permanently secured independent of said coupler and the other end of which engages and normally keeps said coupler at the limit of its forward movement.
6. An automatic coupler for train-pipes of cars comprising a longitudinally yielding body, and having a guide-bar extending from its rear end, and a spring of flat material one end of which is permanently secured independently of said coupler, and the other end of which presses forward against said coupler and is provided with an opening through which said guide-bar extends.
7. An automatic coupler for the train-pipes of cars comprising a longitudinally yielding body having a guide-bar extending rearwardly therefrom, and a substantially C-shaped spring one end of which is permanently secured independent of said coupler, and the other end of which engages and normally keeps said coupler at the limit of its

forward movement, and is provided with an opening through which said guide-bar extends.

8. An automatic coupler for the train-pipes of cars comprising a longitudinally yielding body, and having a guide-bar extending from its rear end which is provided with a fin, and a spring of flat material one end of which is permanently secured independently of said coupler, and the other end of which presses forward against said coupler and is provided with an opening through which said guide-bar and its fin extends.

9. An automatic coupler for the train-pipes of cars comprising a longitudinally yielding body having a guide-bar extending rearwardly therefrom which is provided with a fin, and a substantially C-shaped spring one end of which is permanently secured independent of said coupler, and the other end of which engages and normally keeps said coupler at the limit of its forward movement, and is provided with an opening through which said guide-bar and its fin extends.

10. An automatic coupler for the train-pipes of cars comprising a longitudinally yielding body, and a flat spring adapted to guide the movements and normally keep said coupler at the limit of its forward movement.

11. An automatic coupler for train-pipes of cars comprising a longitudinally yielding body, and a flat spring adapted to guide the longitudinal movement of said coupler, limit its rotative movement and normally keep the same at the limit of its forward movement.

12. An automatic coupler for train-pipes of cars comprising a longitudinally yielding body, and a flat spring having one end permanently secured independently of said coupler and adapted to guide the longitudinal movement of said coupler, limit its rotative movement, and normally keep the same at the limit of its forward movement.

13. The combination with a car, a hanger depending from the end thereof having a suitable opening therein, and a bracket projecting from said hanger, of an automatic coupler extending through said opening, means suspended from said bracket for independently supporting the forward end of said coupler, and a spring engaging the rear of said coupler and normally keeping the same at the limit of its forward movement.

14. The combination with a car, a hanger depending from the end thereof having a suitable opening therein, and a bracket projecting from said hanger, of an automatic coupler extending through said opening, means suspended from said bracket for independently supporting the forward end of said coupler, and a substantially C-shaped spring the upper end of which is permanently secured independently of said coupler and engages the rear end of said coupler and normally keeps the same at the limit of its forward movement.

the same at the limit of its forward movement.

15. The combination with a car, a hanger depending from the free end thereof having a suitable opening therein, and a bracket projecting from said hanger, of an automatic coupler extending through said opening, means suspended from said bracket for independently supporting the forward end of said coupler, and a substantially C-shaped spring the upper end of which is permanently secured independently of said coupler and engages the rear end of said coupler, limits the rotative movement thereof, and normally keeps the same at the limit of its forward movement.

16. The combination with a car, a hanger depending from the end thereof having a suitable opening therein, and a bracket projecting from said hanger, of an automatic coupler extending through said opening, means suspended from said bracket for independently supporting the forward end of said coupler, and a substantially C-shaped spring

the upper end of which is permanently secured independently of said coupler and engages the rear end of said coupler, limits the rotative movement thereof, and normally keeps the same at the limit of its forward movement.

17. The combination with a car and a hanger depending therefrom having an opening in its lower end, of an automatic coupler consisting of an engaging-head, a rear conical-shaped portion or body which passes through said opening, and a narrower central portion or waist connecting the two, and a flat spring adapted to engage the rear end of and normally keep said coupler at the limit of its forward movement.

In testimony whereof I have hereunto set my hand this 10th day of September, A. D., 1906.

FRANK H. RUTHERFORD.
